BLAST FURNACE BOTTOM

Albert B. Agnew, Indiana, Pa., and Frank J. Rief,
Chicago, Ill.

Application January 5, 1944, Serial No. 517,044

1 Claim. (Cl. 266—43)

1

The invention relates to blast furnace bottoms which are formed of a mass of refractory bricks and may be fifteen or more feet in vertical thickness. The top of such a bottom is in contact with the molten iron formed in the furnace, which is at a temperature of about 2300° F., and the bottom sustains the weight of the pig iron and of the furnace burden above it.

In constructing a blast furnace bottom the prevailing practice is to lay plain rectangular brick on end in horizontal courses, bonded by refractory cement. The molten iron at its high temperature so attacks the bricks in the upper course that individual bricks loosen, and, being lighter than the iron, float upwardly in it. When this happens the molten iron may flow below the bottoms of the upper course of bricks and cause large portions of them to loosen and float upwardly. As a result thereof the life of the bottoms is materially shorter than it would be if the only loss of bottom refractory material were due to its normal surface disintegration consequent upon its constant contact with the molten iron.

The object of this invention is to provide a blast furnace bottom formed of bricks that are so provided with ribs and recesses, and so laid in a mass, that each complete brick is engaged by four or more other bricks to restrain it from floating upwardly, and that the paths of downward flow of molten iron between the bricks is effectively interrupted.

The blast furnace bottom provided according to this invention is formed of a mass of bricks that are laid on their ends, each having a pair of opposed vertical faces that are divided into adjacent longitudinal bands. One band on each of these faces is provided with a rib and the other with a coextensive recess which is positioned opposite to the rib. Each such rib is preferably positioned medially of the band, and each preferably has horizontal top and bottom faces effectively to interrupt the path of downward flow of molten iron. The mass of bricks are so arranged that the adjacently disposed bricks medially overlap each other both vertically and horizontally, and that the ribs of each interlock with recesses of adjacent bricks.

The invention is illustrated in the accompanying drawings, of which Fig. 1 is a vertical central sectional view of the lower portion of a blast furnace having a bottom formed according to this invention; Fig. 2 a fragmentary sectional elevation to enlarged scale of some of the main body of brick at the bottom as seen in Fig. 1, the plane

2

of view being indicated by the line II—II, Fig. 4; Fig. 3 a fragmentary sectional elevation of lower courses of the bottom at right angles to Figs. 1 and 2; Fig. 4 a fragmentary plan view to enlarged scale of the bottom; Fig. 5 a perspective view of one of the bricks; and Fig. 6 an isometric view of a plurality of assembled and interlocked bricks forming a portion of the mass at the top of the furnace bottom.

10 The blast furnace, the bottom portion of which is shown in Fig. 1, is of conventional form comprising a generally cylindrical wall 1 which rests upon the outer portion of a furnace bottom 2. The preferred form of bricks 3 for forming the bottom according to this invention is that shown in perspective in Fig. 5, it being there shown resting on its end in the vertically disposed position the bricks occupy in the furnace bottom. While the brick may be of various sizes, it is preferably 12 x 9 x 4½ inches.

15 The brick has a flat top 4, a flat bottom 5, and a pair of opposite flat vertical faces 6 and 7. Its other pair of opposite vertical faces are each divided into adjacent longitudinal vertically-extending bands, the width of each of which is one-half the width of the brick. One of these bands is provided medially with a flat faced rib 8 and the other with an adjacent coextensive and correspondingly shaped recess 9. Rib 8 being one-half the height of a brick and medially positioned, it is adjoined at each end by a recess 10 which is one-half the vertical length of rib 8. Similarly, recess 9 on the other band being one-half the length of the brick and corresponding in size to rib 8, is adjoined at each end by a rib 11 which is half the length of recess 9. These ribs and recesses are the same on both of the opposite sides of the brick, although rib 8 is opposite to recess 9 and half recesses 10 are opposite half ribs 11.

20 While the full length ribs 8 and recesses 9 have been described as being half the length of the brick, and recesses 10 and ribs 11 as being half the lengths of the full size recesses and ribs, it will be understood that ribs 8 are sufficiently less and recesses 9 sufficiently more than half the length of the brick to afford the necessary clearance between boundaries of the ribs and recesses to permit their interlocking with 25 each other when the bricks are laid in a mass to form a blast furnace bottom with refractory cement between adjacent faces. Preferably the top and bottom faces 12 of each rib and the top and bottom faces 13 of each recess are flat and 30 lie in substantially horizontal planes when the

bricks are assembled in a mass. These faces preferably deviate from the horizontal only to the extent that it is necessary to taper them to facilitate pressing the bricks in the usual manner.

As has been stated, in forming a blast furnace bottom according to this invention adjacently disposed bricks medially overlap each other both horizontally and vertically, and ribs of each brick interlock with recesses of adjacent brick. To assemble the bricks in this fashion and at the same time form flat horizontal faces on the upper and lower surfaces of the furnace bottom, it is necessary to use rows of half bricks 15 at the bottom and the top alternating with rows of full length bricks, as shown in Figs. 2 and 4. As shown in Fig. 2 the bricks medially overlap each other vertically so that half ribs 11 of adjacent bricks in a vertical tier interlock with the full length medial recesses 9 in an adjacent brick, and that each full length rib 8 interlocks with the half recesses 10 at the ends of adjoining bricks in the vertical tier. The top and bottom ends 12 of ribs 8 and the top and bottom ends 13 of recesses 9 being horizontal, the vertical path for possible flow and escape of molten iron is effectively interrupted.

The medial overlapping of bricks in a horizontal direction is illustrated in Figs. 3 and 4 which show that the paths of possible flow and escape of molten iron between the edges of the bricks is interrupted. Fig. 3 also illustrates the vertical banding of opposed faces of the bricks, each brick 3 having one of its vertical bands provided with a medial rib 8 and adjoining half of recesses 10, and its adjacent vertical band provided with a recess 9 and adjoining half of ribs 11.

The bricks from which the blast furnace bottom is formed may be readily pressed in the usual manner, and they are provided with a pair of opposed flat faces upon which they may rest for firing without sagging and without liability of being otherwise distorted. When the bricks are laid in the manner shown and explained, each full brick is engaged by horizontal portions of four adjacent bricks effectively to lock it in position and prevent it from floating upwardly in case the refractory cement surrounding it is impaired or destroyed.

According to the provisions of the patent 50 statutes, we have explained the principle of our invention and have illustrated and described what we now consider to represent its best embodiment. However, we desire to have it understood that,

within the scope of the appended claim, the invention may be practiced otherwise than specifically illustrated and described.

We claim:

5 A blast furnace bottom formed of a deep mass of vertically disposed bricks superposed in broken horizontal courses and each brick having a rectangular parallelepiped body with a pair of its opposite vertical faces divided into two adjacent 10 vertically disposed bands of like width, one band on each face being provided medially with a flat faced rib of parallelepiped form which extends substantially half the vertical depth of the brick and with vertically adjacent recesses of like form 15 each extending substantially one-quarter of the vertical depth of the brick, the other band on the same face being provided medially with a co-extensive and correspondingly shaped recess horizontally opposite to said rib and with co-extensive and correspondingly shaped ribs horizontally opposite to said first-mentioned recesses, each of said ribs and recesses on one face being opposite to a corresponding recess and rib, respectively, on the other face, adjacently disposed 20 bricks constituting said mass medially overlapping each other both vertically and horizontally, and the ribs of each brick interlocking with recesses of adjacent bricks, whereby each whole brick throughout the main body of the 25 mass is engaged on each of its said faces by four horizontally adjacent bricks and is thereby restrained from floating upwardly into molten metal and paths of downward flow of molten metal are interrupted by horizontal adjacent 30 faces of the inter-engaging ribs.
